BOTTLE

Anna Fevas, Akron, Ohio

Original application February 21, 1944, Serial No. 523,369. Divided and this application September 29, 1944, Serial No. 556,410

2 Claims.

(Cl. 215—1)

This invention relates to a container or bottle of a peculiar and novel construction for use in an inverted position in an electrically heated applicator.

This application is a divisional case, growing out of my co-pending application, Serial No. 523,369, filed February 21, 1944, and entitled "Electrically heated applicator."

An object of the invention is the construction of a container or bottle with a comparatively solid, integral throat, having therein a peculiar and novel passage, which passage has a dual function.

Another object of the invention is the construction of the bottle, having a novel arrangement, allowing it to operate in an inverted position, whereby an air tubing is partly wrapped or folded around the neck of the bottle and partially extends into same, with a very small outlet provided at the side of said tubing for the contents of the bottle to pass out under air pressure within said bottle.

With the foregoing and other objects in view, my invention comprises certain novel constructions, combinations, and arrangements of parts as will be hereinafter fully described, illustrated in the accompanying drawing, and more particularly pointed out in the appended claims.

In the drawing:

Figure 1 is an enlarged perspective view of a container or bottle constructed in accordance with this invention, while

Figure 2 is a vertical central sectional view of the same.

Figure 3 is a sectional view, taken on line 3—3, Figure 2, and looking in the direction of the arrows.

Figure 4 is a fragmentary enlarged, vertical sectional view of an electrically heated applicator, showing my bottle in an operating position therein.

Referring to the drawing by numerals, I designates the body of the container or bottle, which has in its side a longitudinally extending groove, the full height of the bottle. The bottle has a deep, solid throat 3, which is provided with a peculiar passage 4; this passage 4 comprises a large tube-receiving section 5, and a small outlet section 6. Suitable threads 7, are on the neck of

the bottle, whereby a cap or closure of any common type can be used when desired.

It is to be noted that the passage 4 is off center of the throat 3 to place the large section 5 close to and registering with the top end of groove 2. This facilitates the folding or wrapping of the air tubing 8 around the bottle, as clearly seen in Figure 4. By reason of the depth of the solid throat 3, the passage 5 is of sufficient depth to materially assist in holding the tubing upright, whereby the inner end of the tubing 8 is always held near the bottom of the bottle for efficient operation.

As seen in Figure 4, the bottle operates in an inverted position, with the upper portion of the bottle resting on the supporting collar 9 of the applicator casing 10. For detailed description of said applicator, reference may be had to my co-pending application Serial No. 523,369, hereinbefore referred to.

The small outlet section 6 of passage 4 is desirable, because it permits only a small quantity of the contents of the bottle to be discharged at a time. This construction of the novel passage is for dual function, to wit: it receives the air tubing and also permits small quantities of the contents of the bottle to be discharged. Further, this bottle is especially adaptable for use in an inverted position, and in an applicator.

What I claim is:

1. As a new article of manufacture, a container or bottle comprising a body provided with an integral, solid, deep throat, and being provided in its side with a full-length tubing-receiving groove, and said solid, deep throat being provided only with a passage comprising a relatively large tubing-receiving section and a relatively small outlet section.

2. As a new article of manufacture, a container or bottle, comprising a body provided with an integral, solid, deep throat, and being provided in its side with a full-length tubing-receiving groove, and said solid, deep throat being provided only with a passage off-center of the throat, and said passage comprising a relatively large tubing-receiving section close to the top end of said groove and registering with said groove, and said passage also comprising a relatively small outlet section at the center of said throat.

ANNA FEVAS.
